CLAIM

The ornamental design for a compartmented bowl, as shown.

DESCRIPTION

FIG. 1 is a first side elevational view of a compartmented bowl showing my new design;

FIG. 2 is a top view thereof;

FIG. 3 is a second side elevational view thereof, opposite to said first side elevational view;

FIG. 4 is a third side elevational view thereof, 90 degrees from said first side elevational view;

FIG. 5 is a bottom view thereof; and,

FIG. 6 is a fourth side elevational view thereof, opposite to the side view of FIG. 4.

FIG. 1

FIG. 2

FIG. 3

FIG. 4

FIG. 5

FIG. 6
